INSULATING SHIELD FOR ELECTROLYTIC TANKS

Selden Bradley Sanford, Yonkers, N. Y., and William George Nutzel, Nutley, N. J., assignors to Otis Elevator Company, New York, N. Y., a corporation of New Jersey

Application December 27, 1943, Serial No. 515,838

2 Claims. (Cl. 204—279)

1

The invention relates to apparatus for electrolytic processes.

In practicing electrolytic processes it is essential that there be no direct electrical contact between the electrodes. In some of these processes, a metal lining for the tank is utilized as an electrode. This is the case, for example, in the process of forming artificially on aluminum articles a protective coating composed substantially of aluminum oxide, known as "anodizing." While the process employed to form such oxide coatings on aluminum may vary, depending principally upon the use or after treatment of the article, in one process widely used, the aluminum surface is treated electrolytically as anode in an aqueous solution of sulphuric acid. In this process a lead lined tank is employed and this lining is utilized as the cathode.

The object of the invention is to provide a durable insulating shield for use in an electrolytic processing tank, especially a metal lined tank in which the lining is utilized as an electrode.

In carrying out the invention according to the preferred arrangement, the insulating shield is formed of a plurality of spaced main members and a plurality of cross members extending between the main members. Along the bottom, the main members extend across the tank and the cross members longitudinally of the tank. Along the sides, the main members extend vertically and serve as posts while the cross members extend around the sides and ends of the tank, preferably in the form of a spiral. Between the main members and preferably parallel thereto are warp members with which the cross members are interwoven to provide a mesh like structure. All of these members are of an insulating plastic which is chemically resistant to the electrolyte. Thus a basket like insulator is formed which does not restrict the flow of current between electrodes, which obviates any direct contact between electrodes, and which lasts indefinitely.

Features and advantages of the invention will become apparent from the following description and appended claims.

The invention will be described as applied to an "anodizing" tank.

In the drawing:

Figure 1 is a plan view of an electrolytic processing tank embodying the invention; and

Figure 2 is a view in section, taken along the line 2—2 of Figure 1.

Referring to the drawing, the tank 10 may be made of any suitable material, such as sheet

2

iron or reinforced wood. It is provided with a lead lining 11 which is not affected by an aqueous solution of sulphuric acid employed as the electrolyte. In the "anodizing" process, the temperature of the solution is an important factor and for this reason a coil 12 of lead pipe is provided within the tank through which hot or cold water may be passed to control the temperature. It is also important that the temperature throughout the solution be uniform. To obtain this result, the solution is agitated by air admitted to the tank through the lead pipe 13. This pipe has a dead end and runs longitudinally of the tank along the bottom and midway between the sides. Outlet holes not shown, are provided in the pipe through which the air passes into the electrolyte.

The insulating shield may be fabricated in three sections, one of which forms the bottom 15 and the other two the sides 16. Each section comprises a plurality of main members 17, a plurality of cross members 18 and a plurality of warp members 20. These members are of non-metallic electrolyte resistant material and are preferably made of tubing. A bendable plastic material such as "Saran" which is synthetic resin comprising polymers derived from vinylidene chloride has been found especially suitable for this purpose.

The cross members are of smaller diameter than the main members and extend through holes 21 drilled in the main members. Templates are employed in drilling the holes in the main members. These holes are equally spaced so that when a section is formed these cross members are equidistant and parallel. The cross members for the bottom section are at right angles to the main members. As regards the sides, the main members, after being drilled, are sawed off at increasing distances from the bottom so that when the shield is installed these cross members may form a continuous spiral.

The warp members 20 are positioned between the main members in parallel relation thereto. The warp members may be of the same diameter as the cross members and may be either of straight pieces of tubing as illustrated adjacent the ends of the bottom section or of longer pieces of tubing bent over upon themselves to form two warp members joined at one end in the nature of a hairpin as more clearly shown in Figure 2 for a side section. The cross members 18 are interwoven with the warp members, being bent alternately under and over the warp members as illustrated to form a basket weave construction.

After each side section has been assembled it is bent at the corners to fit the tank inside the lead coil. With material such as "Saran" a permanent set may be made by immersing in boiling water for about a minute and then cooling in tap water. The side sections are then joined by joining the ends 22 of the abutting cross members with tubular inserts (not shown). The bottom section is inserted in the tank first and is bent down on each side from the air pipe 13. The joined side sections are then inserted, meshing them at the bottom with the bottom section to hold this section in place when the electrolyte is admitted to the tank. The main members of the side section may be close together at the corners 15 as illustrated to facilitate meshing with the bottom section. The bottom section may also be tied to the lead pipe 12 to assist in holding it in position.

The number and size of the various members making up the insulating shield may vary depending upon the particular installation. For example, in a tank, 4 feet wide by 8 feet long by 5 feet deep, for which an insulating shield has been constructed, the main members are made of 1 inch tubing and the cross members and warp members of $\frac{3}{8}$ inch tubing. Most of the main members are spaced about 17 inches and the cross members are spaced $1\frac{1}{2}$ inches. The warp members are spaced about $2\frac{1}{4}$ inches. This gives a sufficiently stiff construction to insure no direct contact of anode with the cathode or pipes while at the same time it provides meshes of ample size not to materially restrict the circulation of electrolyte or flow of current between electrodes.

While described in connection with a tank utilized for "anodizing," the invention has other applications. As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

1. An insulating shield for an electrolytic processing tank having a metal lining serving as an

electrode comprising; a bottom portion for shielding the bottom of the tank; and an upright portion for shielding the side and end walls of the tank; each portion comprising a plurality of spaced main members, each having a plurality of cross apertures equally spaced lengthwise thereof, a plurality of cross members extending through said apertures, and a plurality of warp members between and parallel to said main members with which the cross members are interwoven, the main members of the upright portion extending vertically and having their apertures positioned therein so that the cross members of such portion form an upwardly extending spiral, and all of said members being of bendable tubing of synthetic resin resistant to the chemical action of the electrolyte.

2. An insulating shield for an electrolytic processing tank having a metal lining serving as an electrode comprising; a section for shielding the bottom of the tank; and a pair of sections for shielding the side and end walls of the tank; each section comprising, a plurality of spaced main members each having a plurality of cross apertures equally spaced lengthwise thereof, a plurality of cross members extending through said apertures, and a plurality of warp members between and parallel to said main members with which the cross members are interwoven, the main members of the bottom shielding section extending crosswise of the bottom of the tank and those of said pair of side and end shielding sections extending vertically, said pair of side and end shielding sections being bent to fit the tank at the corners and the ends of the cross members thereof being joined in abutting relationship with the relationship of said apertures in the main members thereof such that these cross members form a continuous upwardly extending spiral, 40 said pair of side and end shielding sections intermeshing with the bottom shielding section when the sections are in place in the tank, and all of said members of all sections being tubing of thermoplastic synthetic resin comprising polymers derived from vinylidene chloride.

SELDEN BRADLEY SANFORD,
WILLIAM GEORGE NUTZEL.
